UNITED STATES PATENT OFFICE.

RULON H. DAVIS, OF SALT LAKE CITY, UTAH.

FOLDING UMBRELLA.

Application filed September 1, 1923. Serial No. 660,600.

The invention has relation to an umbrella, parasol or analogous article for affording protection against the rays of the sun and rain, and has for its primary object the provision of an article of this nature which may be reduced to compact form for convenience of transportation, or which may be used as a cane, as required.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

20 Referring to the accompanying drawings forming a part of the application:

Figure 1 is a view in elevation of an umbrella embodying the invention, showing the same extended,

25 Figure 2 is a central vertical section view showing the parts folded,

Figure 3 is a detail sectional view of the upper end of the stick and the notch thereon to which the ribs are attached,

30 Figure 4 is a top plan view of the runner,

Figure 5 is a fragmental longitudinal section of a rib,

Figure 6 is a cross section of the rib on the line 6—6 of Figure 5,

35 Figure 7 is a detail view of the handle, and

Figure 8 is a detail view of a modified form of handle.

Corresponding and like parts are referred to in the following description and designated in the several views of the drawings by like reference characters.

The umbrella comprises a sectional stick embodying the parts 1 and 2 which preferably have a telescopic arrangement and which when extended are held in the adjusted position by means of a suitable catch 3. A sleeve or runner 4 is loosely mounted upon the stick and carries a collar 5 to which the stretchers are pivotally connected. The

sleeve 4 is adapted to be confined upon the stick between suitable stops or in any preferred way and is provided upon its inner side with a longitudinal groove 6 which is adapted to clear the lowermost stop to admit of lowering the sleeve upon the stick when required. The collar consists of a ring 5 mounted upon the sleeve 4 and held thereon between upper and lower stops. Suitable stops 8' on the stick engage the runner 4 and hold it in the required adjusted position. The runner 4 is grooved upon its inner side at 6, as hereinbefore described to clear the upper stop 8'. The stops 8' face in opposite directions and engage opposite ends of the runner 4 to hold the same in lowered position upon the stick when the umbrella is raised.

Each of the ribs comprises an upper section 9 and a lower section 10, the latter being pivoted to the notch 16 and the section 10 telescoping therein. The braces 8 are pivoted to the sections 9 which are slideable upon the sections 10. When the umbrella is folded, the runner 4 is adjacent the notch 16 and the braces 8 lie between the stick and the ribs, the latter being telescoped. The covering 11 is attached at its outer edge to the tips of the rib sections 9 and to the swinging ends of the sections 10 and when the umbrella is folded, the outer portion of the covering folds upon itself and is adapted to be wrapped about the stick and frame and is held in place by means of a tape or strap 12.

The handle is divided longitudinally and comprises the sections 13 and 14 which are hingedly connected to swing into open position to admit of folding and unfolding the umbrella. A suitable catch 15 holds the sections 13 and 14 when closed. The sectional handle may be of uniform diameter throughout, or one end may be enlarged. The section 2 of the stick is pivotally connected to the handle so that when the umbrella is folded it may be turned into position to be enclosed within the sections of the handle.

What is claimed is:

1. In combination with a folding um-

rella, a hollow handle composed of sections that may be opened longitudinally and having the umbrella pivoted thereto, the parts being arranged to admit of the umbrella when folded being housed within the handle.

2. In a folding umbrella, a hollow handle comprising sections that may be opened lon-

gitudinally, a stick, a member rotatably mounted in one end of one of the sections of the hollow handle and carrying the stick, and the umbrella canopy being foldable and collapsible for housing in said handle. 10

In testimony whereof I affix my signature.
RULON H. DAVIS.
